CLAIM

The ornamental design for a shoe as shown and described.

DESCRIPTION

FIG. 1 is a bottom front perspective view of a shoe showing my new design;

FIG. 2 is a bottom view thereof;

FIG. 3 is a bottom rear perspective view thereof; and,

FIG. 4 is an enlarged bottom view thereof showing the design as shown in FIG. 2, with environment removed for clarity purposes.

The unshaded broken line region within the shaded area forms no part of the claimed design. The broken line immediately adjacent to and surrounding the shaded area defines the peripheral bounds of the claimed design and forms no part thereof. The broken lines depicting the remainder of the shoe form no part of the claimed design.
